CIRCUIT INTERRUPTER

James M. Cumming, Turtle Creek, Pa., assignor to
Westinghouse Electric Corporation, East Pitts-
burgh, Pa., a corporation of Pennsylvania

Application September 12, 1946, Serial No. 696,571

9 Claims. (Cl. 200—150)

1

This invention relates to circuit interrupters in general and more particularly to improved arc-extinguishing structures therefor.

A general object of my invention is to provide an improved circuit interrupter in which the arcs established therein will more quickly and effectively be interrupted than heretofore.

A further object of my invention is to provide a circuit interrupter using only a small quantity of fluid, and preferably of the single bushing type.

A more specific object of my invention is to provide an improved circuit interrupter in which the structural positioning of the several parts is improved over the constructions employed heretofore. More specifically, my invention is concerned with operating constructions which will positively establish the arcs and will effectively interrupt them quickly over the entire current range.

Another object is to provide an improved arc-extinguishing unit in which a pair of interrupting chambers are disposed at opposite ends of the unit and in which an improved pressure-generating chamber is provided intermediate the ends of the unit. Preferably, an improved low current piston construction is disposed within the pressure-generating chamber to facilitate the interruption of low currents where the pressure generated at the pressure-generating arc is not sufficient to provide the requisite fluid flow toward the interrupting arcs.

Another object is to provide an improved contacting holding engagement between the actuating movable contact and the operating rods within the unit which cause positive movement of the contact structure within the arc-extinguishing unit.

Further objects and advantages will readily become apparent upon a reading of the following specification taken in conjunction with the drawings, in which:

Figure 1 is a side elevational view of a complete circuit interrupter embodying my invention;

Fig. 2 is an enlarged side elevational view, partly in vertical section, of the improved circuit interrupter of Fig. 1;

Fig. 3 is a vertical sectional view through the improved arc-extinguishing unit of my invention on the line III—III of Fig. 5, the contacts being shown in the partly open circuit position and the current conditions being assumed to be high so that the low current piston is held back;

Fig. 4 is a sectional view taken along the line

2

IV—IV of Fig. 3 looking in the direction of the arrows;

Fig. 5 is a sectional view taken along the line V—V of Fig. 3 looking in the direction of the arrows.

Fig. 6 is an enlarged fragmentary view of a contact structure in which the taper is so large that the two contacts will not hold together, and

Fig. 7 is an enlarged fragmentary view of my improved contact holding device taken on the line VII—VII of Fig. 3 in the direction of the arrows.

Referring to the drawings, and more particularly to Fig. 1 thereof, the reference numeral 1 designates a base upon which is mounted vertically extending structural framework comprising a plurality of vertical angle irons 2 braced by diagonally extending angle irons 3 and supporting at the upper end thereof a horizontally extending support generally designated by the reference numeral 4. The support 4 supports rigidly in position a circuit interrupter of the oil-poor type generally designated by the reference numeral 5 and including a high voltage condenser bushing 6 extending through a support

25 plate 7 and having an arc-extinguishing unit 8 threadedly secured and clamped to the lower end of the bushing as at 9.

The arc-extinguishing unit 8 is immersed in a suitable arc-extinguishing liquid 10 filling the casing 11 to the level 12. The casing 11 comprises an internally disposed cylindrical insulating cylinder 13 and an externally disposed porcelain cylinder 14. Preferably, the insulating cylinder 13 is maintained in tension and the porcelain cylinder 14 maintained in compression. This is accomplished in the present instance by employing a plurality of spring washers 15, the outer periphery of which make engagement with a metallic cylindrical member 16 having the upper end thereof bearing against the lower end of the porcelain casing 14. The spring washers 15 are bolted at their inner side by bolts 17 to an annular clamp 18 secured to the lower end of the insulating tube 13. The clamp 18 also supports 40 a stationary guide casting 19 which serves to guide during the opening and closing operations of the interrupter a lower movable contact 20.

The lower movable contact 20 is pivotally connected at 21 to an insulating operating rod 22 pivotally connected at its upper end at 23 to a crank 24, the right-hand end of which is rigidly secured to an operating shaft 25. The operating shaft 25 may be actuated externally of the metallic housing 26 by a crank arm 27 (Fig. 2). Consequently, during the opening and closing

operations the crank arm 21 is rotatively operated to cause through the linkage 22, 24 vertically reciprocating motion of the lower movable contact 20.

Certain of the mounting features herein described are set forth and claimed in United States patent application, filed May 19, 1945, Serial Number 594,634, by Leon R. Ludwig and Benjamin F. Baker, and assigned to the assignee of this invention.

Referring more particularly to Fig. 3 which shows enlarged a vertical sectional view through the arc-extinguishing unit 8, it will be observed that in my improved construction I have employed an intermediately disposed casting member 28 which has its ends bolted to metallic plate members 29, 30. Two sets of insulating tie rods 31 (Fig. 4) secure the two stacks of insulating plate members to the metallic plates 29, 30 and to the top and bottom metallic plates 32, 54 of the unit 8. Preferably, the top metallic plate 32 is an integral part of the contact foot 33 which is clamped to the lower end of the bushing 6.

The arc-extinguishing unit 8 includes an upper interrupting chamber generally designated by the reference numeral 34, a lower interrupting chamber generally designated by the reference numeral 35 and a centrally or intermediately positioned pressure-generating chamber, generally designated by the reference numeral 36.

Carriage means including two insulating operating rods 37 are utilized in the construction shown in Fig. 3 and extend interiorly longitudinally of the unit 8, having their lower ends bridged by a conducting bridging member 38, and their upper ends bridged by a second conducting bridging member 39. Preferably, the upper ends of the rods 37 make threaded engagement, as at 40, with the conducting bridge 39. Studs 41 are inserted into the lower ends of the operating rods 37 and cooperate with nuts 42 to maintain the operating rods 37 securely clamped to the lower conducting bridge 38.

Extending upwardly through an outer insulating sleeve 43 from the central portion of the upper conducting bridging member 39 is an upper movable interrupting contact 44. The movable contact 44 cooperates with an upper relatively stationary contact 45 to establish a first or upper interrupting arc 46 within the interrupting chamber 34.

The upper movable interrupting contact 44 is threaded secured to a movable pressure-generating contact 47 which cooperates with a relatively stationary pressure-generating contact 48 to establish a pressure-generating arc 49 within the pressure-generating chamber 36.

Extending upwardly from the central portion of the lower conducting bridge member 38 is a movable interrupting contact 50 which cooperates with a relatively stationary interrupting contact 51 to establish a lower or second interrupting arc 52 within the lower interrupting chamber 35. Compression springs 53 encircle the lower ends of the operating rods 37, being disposed between the conducting bridge 38 and the lower metallic plate 54 of the lower interrupting chamber 35. Thus, the compression springs 53 bias the operating rods 37 and both bridging members 38, 39 downwardly toward the circuit opening position.

I have provided a plurality, in this instance four, finger contacts 56 (Fig. 5) disposed in recesses 59 provided in the intermediate casting 28 and secured thereto by any suitable means, such

as the screws 60. The finger contacts 56 bear against the side wall 57a of a piston 57 movable within an operating cylinder 61 formed as an integral part of the casting 28 (Fig. 5). The walls of the casting 28 also provide a plurality, in this instance four, fluid conducting passages 62 and shown more clearly in Figs. 3 and 5. The piston 57 is biased downwardly by a compression spring 63 which also serves to provide the requisite contact pressure between the pressure-generating contacts 47, 48 when in the closed circuit position of the interrupter, it being noted that the relatively stationary pressure-generating contact 48 is secured to and movable with the piston 57.

From the foregoing discussion it will be apparent that in the closed circuit position of the interrupter the electrical circuit therethrough includes lower line terminal 55, stationary guide casting 19, lower movable contact 20, conducting bridge 38, lower movable interrupting contact 50, lower relatively stationary interrupting contact 51, metallic plate 30, intermediate casting 28, finger contacts 56 (Fig. 5), conducting piston 57, relatively stationary pressure-generating contact 48, movable pressure-generating contact 47, upper movable interrupting contact 44, upper relatively stationary interrupting contact 45, top metallic plate 32, contact foot 33, and through the terminal stud 58 disposed interiorly of the high voltage condenser bushing 6.

When it is desired to open the electrical circuit through the interrupter or when overload conditions exist in the electrical circuit controlled by the interrupter, suitable mechanism, not shown, is actuated to cause counterclockwise rotative movement of the crank arm 21. This rotative motion of the crank arm 21 causes movement of the intermediately disposed linkage 22, 24 and downward motion of the lower movable contact 20.

I provide a substantially 16° semi-holding tapered orifice contact 64 (see Fig. 7) which makes contacting engagement with the contact 20. This type of moving contact eliminates fingers and has a shock resisting effect in closing. This contact connection between the contacts 64, 20 gives a positive connection in opening because of the angle of the taper connection which has been so designed as to need a slight tap or knock to disengage. So because of the substantially 16° taper, the bridge 38 moves downwardly with the movable contact 20 during the opening operation. Thus the angle α in Fig. 7 is 8°, and must not be too great. Fig. 6 shows a contact construction in which α is too large and hence the contact 20 will not hold to the contact 64a. Angle α must be less than the angle of friction of rest (or angle of repose); or tan. α must be less than the coefficient of friction of rest (or of static friction). For metals on metals α varies from 8° to 17.5°.

The downward motion of the conducting bridge 38 simultaneously causes downward motion of the operating rods 37 and downward motion of the two movable interrupting contacts 44, 50 from their respective relatively stationary interrupting contacts 45, 51 to simultaneously draw two interrupting arcs 46, 52 within the respective interrupting chambers 34, 35. Also at the same time that the separation takes place between the two pairs of interrupting contacts, there also takes place separation between the pressure-generating contacts 47, 48 to draw the pressure-generating arc 49 within the pressure-generating chamber 36. Consequently, with the construc-

tion which I have employed, there results the simultaneous establishment of an intermediately disposed pressure-generating arc and two interrupting arcs within the two interrupting chambers 34, 35 disposed at opposite ends of the arc-extinguishing unit 8.

The establishment of the pressure-generating arc 49 creates pressure within the liquid, in this instance, circuit breaker oil, disposed within the pressure-generating chamber 36 to force said liquid upwardly through the fluid conducting passages 62 and into the upper interrupting chamber 34. Also, the oil is forced downwardly from the pressure-generating chamber 36 through two vertically disposed fluid conducting passages 65 into the lower interrupting chamber 36.

The interrupting chambers 34, 35 are of the type set forth in United States patent application, filed November 11, 1942, Serial No. 465,244, by Leon R. Ludwig, Winthrop M. Leeds and Benjamin P. Baker, now United States Patent 2,406,469, issued August 27, 1946, and assigned to the assignee of the instant application. For the purpose of illustrating my invention it is merely necessary to state that the fluid flowing downwardly through the fluid conducting passages 65 passes radially inwardly through three pairs of inlet passages 66, as more clearly shown in Fig. 4, to contact the interrupting arc 52 and pass through orifices 67 to pass out of the interrupting chamber 35 through oppositely disposed vent passages 68. Reference may be had to the aforesaid Patent 2,406,469 for the constructional details of the several plates forming the interrupting chambers 34, 35. The interrupting action which takes place in the upper interrupting chamber 34 is identical to that which takes place in the lower interrupting chamber 35, the fluid passing upwardly through the passages 62 and into two vertically extending passages 69 which communicate with a plurality of pairs of inlet passages 66. Again the fluid after contacting the interrupting arc 46 passes through orifices 67 and out of the interrupting chamber 34 through oppositely disposed vent passages 68 (Fig. 4).

During the interruption of high powers, the pressure generated at the pressure-generating arc 49 will be sufficient to hold the piston 57 upwardly in its charged position against the downward bias exerted by the compression spring 63. However, during the interruption of low powers, where the pressure generated at the pressure-generating arc 49 may be insufficient to establish the requisite fluid flow, then the bias of the compression spring 63 will be sufficient to overcome the arcing pressure within the pressure-generating chamber 36 and cause downward motion of the piston 57 within the operating cylinder 61 formed by the casting 28. The downward movement of the piston 57 will force the oil upwardly through the passages 62 into the interrupting chamber 34 and downwardly through the passages 65 into the interrupting chamber 35.

Consequently, I have provided piston means operable during low current interruption to speed up the extinction process exerted upon the two interrupting arcs 46, 52.

After the arcs have been extinguished, the plunger 70 formed of insulating material and secured to the bridging member 39 moves into the cup-shaped dashpot 71 to halt the downward motion of the bridges 38, 39 and operating rods 37. Thus, I have provided a dashpot operable to cushion the stopping of the movable contact

structure near the end of the opening stroke. When the plunger 70 enters the dashpot 71 to thereby halt the downward motion of the bridges 38, 39, the lower movable contact 20 is forcibly withdrawn from the slight taper afforded by the contact 64. This provides an isolating gap in clear oil outside of the arc-extinguishing unit, in the fully open circuit position of the interrupter, as shown more clearly in Fig. 2.

- 10 During the closing operation, the contact 20 is moved upward by clockwise rotation of crank arm 21 to thereby engage the contact 64. The contact 64 is forced upwardly with the contact 20 against the bias exerted by the compression springs 53 to simultaneously cause the closing of both pairs of interrupting contacts and the pair of pressure-generating contacts. Also, the raising of the movable pressure-generating contact 47 causes upward charging movement of the 20 piston 57 to force the latter to its upper raised position.

From the foregoing description, it will be apparent that I have provided an improved arc-extinguishing unit of the type establishing two 25 interrupting arcs and a pressure-generating arc simultaneously. The simultaneous operation results in high speed interruption. Also, the construction is positive because of the provision of the 16° taper of the contact 64. By such a contact construction, the operating rods 37 are forcibly moved downwardly in a simplified manner and there results immediately positive formation of the pressure-generating arc and the two interrupting arcs. The interrupting chambers are 30 operable to cause effective fluid flow toward the interrupting arcs to consequently bring about their interruption, and the piston 57 assures speedy interruption of the low powers.

The compression spring 63 not only biases the 40 piston 57 to its downward open position but also provides the requisite contact pressure between the pressure-generating contacts 48, 47. The dashpot 71 cushions the stopping of the movable contact structure and permits the lower movable contact 20 to be forcibly withdrawn from the unit 8 to provide the isolating gap in the open circuit position of the interrupter.

It will be noted that the constructional features 50 of my improved type of interrupter are exceedingly simple and positive in operation. The provision of the pressure-generating arc at the central portion of the unit 8 permits upward and downward fluid flow toward the interrupting chambers disposed at the ends of the arc-extinguishing unit 8. Also, the upward and downward forces tend to balance or neutralize the 55 stresses imposed upon the unit 8.

Although I have shown and described a specific structure, it is to be clearly understood that 60 the same was merely for the purpose of illustration and that changes and modifications may readily be made therein by those skilled in the art without departing from the spirit and scope of the appended claims.

65 I claim as my invention:

1. In a circuit interrupter, an operating cylinder, a piston operable within the cylinder, a contact secured to and movable with the piston, another contact cooperable with the said contact to establish an arc, an aperture provided in the piston, and contact means including a contact rod carrying the said other contact movable through the aperture to move the piston in sliding relationship to its charged position.

70 2. In a circuit interrupter, an arc-extinguish-

ing unit, means defining a pair of vented interrupting chambers disposed at opposite ends of the unit, means defining a pressure-generating chamber disposed intermediate the ends of the unit, a pair of interrupting contacts separable in each interrupting chamber, a pair of pressure-generating contacts positioned within the pressure-generating chamber, piston means disposed within the pressure-generating chamber and including a piston operable within an operating cylinder, and rod means extending through the piston and operating cylinder in sliding relationship for simultaneously causing the separation of the three pairs of contacts and also closing charging movement of the piston.

3. In a circuit interrupter, movable contact structure, a movable contact carriage having a limited degree of motion for causing the actuation of the movable contact structure, means defining an orifice contact carried by the carriage, and a rod-shaped movable contact engageable with the orifice contact to cause actuation of the carriage.

4. In a circuit interrupter, a movable contact carriage having a limited degree of motion, an orifice contact carried by the carriage, a rod-shaped movable contact engageable with the orifice contact to cause actuation of the carriage, and the angle of taper being substantially 16°.

5. In a circuit interrupter of the liquid break type, an elongated arc-extinguishing unit, a vented interrupting chamber disposed at one end of the unit, a pressure-generating chamber disposed intermediate the ends of the unit, a piston chamber positioned adjacent the pressure-generating chamber, a piston movable within the piston chamber, a second vented interrupting chamber disposed adjacent the other end of the unit, a pair of separable contacts disposed in each interrupting chamber and also within the pressure-generating chamber, and movable carriage means extending through the piston chamber in sliding relationship thereto for simultaneously causing the separation of the three pairs of contacts and charging of the piston.

6. In a circuit interrupter of the liquid break type, an elongated arc-extinguishing unit, a vented interrupting chamber disposed at one end of the unit, a pressure-generating chamber disposed intermediate the ends of the unit, a piston chamber positioned adjacent the pressure-generating chamber, a piston movable within the piston chamber, a second vented interrupting chamber disposed adjacent the other end of the unit, a pair of parallel extending operating rods, a rod-shaped movable contact extending through the piston chamber and secured to the operating rods to cause charging of the piston, a relatively stationary contact cooperable with the rod-shaped contact to establish an interrupting arc in the vented interrupting chamber, a movable pressure-generating contact secured to the rod-shaped contact and cooperable with a relatively stationary pressure-generating contact to establish a pressure-generating arc within the pressure-generating chamber, and a second rod-shaped movable contact secured to the operating rods and cooperable with a relatively stationary contact to establish a second interrupting arc within the other interrupting chamber.

7. In a circuit interrupter of the liquid break type, an elongated arc-extinguishing unit, a vented interrupting chamber disposed at one end of

the unit, a pressure-generating chamber disposed intermediate the ends of the unit, a piston chamber positioned adjacent the pressure-generating chamber, a second vented interrupting chamber disposed adjacent the other end of the unit, a pair of parallel extending operating rods, a rod-shaped movable contact extending through the piston chamber and secured to the operating rods, a relatively stationary contact cooperable with the rod-shaped contact to establish an interrupting arc within the vented interrupting chamber, a movable pressure-generating contact secured to the rod-shaped contact and cooperable with a relatively stationary pressure-generating contact to establish a pressure-generating arc within the pressure-generating chamber, a second rod-shaped movable contact secured to the operating rods and cooperable with a relatively stationary contact to establish a second interrupting arc within the other interrupting chamber, a piston operable within the piston chamber, and the relatively stationary pressure-generating contact being secured to and movable with the piston.

8. In a circuit interrupter of the liquid break type, an elongated arc-extinguishing unit, a vented interrupting chamber disposed at one end of the unit, a pressure-generating chamber disposed intermediate the ends of the unit, a piston chamber positioned adjacent the pressure-generating chamber, a piston movable within the piston chamber, a second vented interrupting chamber disposed adjacent the other end of the unit, movable carriage means including a pair of parallel extending operating rods, a rod-shaped movable contact extending through the piston chamber in sliding relation with respect to the piston to cause the charging thereof and secured to the operating rods, a relatively stationary contact cooperable with the rod-shaped contact to establish an interrupting arc within the vented interrupting chamber, a movable pressure-generating contact secured to the rod-shaped contact and cooperable with a relatively stationary pressure-generating contact to establish a pressure-generating arc within the pressure-generating chamber, a second rod-shaped movable contact secured to the operating rods and cooperable with a second relatively stationary contact to establish a second interrupting arc within the other interrupting chamber, and a rod-shaped movable disconnecting contact to cause actuation of the movable carriage means.

9. In a circuit interrupter, a movable carriage, an orifice-shaped contact secured to the movable carriage, a rod-shaped movable contact engageable with the orifice-shaped contact to cause actuation of the carriage, and the angle of taper being between 16° and 35°.
